UNITED STATES PATENT OFFICE

RICHARD F. KRAUSE, OF MASSILLON, OHIO

DESIGN FOR A DRIP COFFEEPOT

Application filed June 28, 1930. Serial No. 36,225. Term of patent 7 years.

To all whom it may concern:

Be it known that I, RICHARD F. KRAUSE, a citizen of the United States, residing at Massillon, in the county of Stark and State of Ohio, have invented a new, original, and ornamental Design for Drip Coffeepot, of which the following is a specification, reference being had to the accompanying drawing, forming part hereof.

Fig. 2, is a side elevation of the hot water and ground coffee receptacle thereof.

The opposite side of the pot bears the ornamentation shown in Figure 1.

I claim:

The ornamental design for a drip coffee pot, as shown and described.

RICHARD F. KRAUSE.
